PLASTIC CARRIER FOR BOTTLES
Walter E. Hidding, 505 Banbury Road,
Arlington Heights, Ill.Filed Feb. 23, 1965, Ser. No. 440,659
16 Claims. (Cl. 294—31.2)

This is a continuation-in-part application of my co-pending application Serial No. 309,256 which was filed September 16, 1963, now abandoned.

This invention relates generally to carrier devices and more particularly to a carrier or support for use with bottles and other containers in the dairy, pharmaceutical, and analogous industries.

Carriers or supports which include a flexible handle element have been developed heretofore for use with various types of bottles and containers. However, these prior art carriers have incorporated a continuous, generally circular band or strap for gripping the container. The resiliency of the material from which the band was fabricated has, because of the continuous nature of the band, been relied on to permit expansion of the band for effectuating assembly to a container and to achieve subsequent gripping of the container. These prior art carriers therefore were restricted in the tightness of the grip which could be obtained and were also restricted in the size of the enlargement on the container which could be negotiated by the band. Heating of the band has frequently proved necessary to its assembly with a container, and this procedure has proved to be both costly and inconvenient.

Accordingly, a general object of the present invention is to provide a new and improved carrier support for bottles and other containers.

Another object of the invention is to provide a support device that is assembled to a container while in a substantially relaxed condition.

Still another object of the invention is to provide a multiple element, container support arrangement in which the handle element is biased into a generally lateral relationship with the band element.

And still another object of the invention is to provide a support device that is capable of developing a very tight grip of the container to which it is assembled.

Yet another object of the invention is to provide a support device arranged to preserve its retention of the container to which it has been assembled.

And yet another object of the invention is to provide a multiple element container support arranged to preserve the connection of the several component elements.

These and other objects and features of the invention will become more apparent from a consideration of the following disclosure.

A support in accord with the invention includes a number of arcuate collar sections which are arranged in an endless series and which lie in substantially the same plane. Outwardly extending lugs are connected to each of the collar sections adjacent the opposite ends thereof, and a leading lug of one section is aligned with a trailing lug of the next adjacent section. In order to interconnect the collar sections, a rotatable coupling member is provided for each adjacent pair of the aligned leading and trailing lugs, the coupling member having a cam opening which surrounds the aligned lugs. This cam opening in the coupling member is fashioned to possess a major diameter which allows spacing of the surrounded lugs for assembly of the support to a bottle or other container, and the cam opening is further fashioned to possess a minor diameter which, upon rotation of the coupling member, acts to cam the surrounded lugs closely together for drawing the collar sections tightly about the encom-

2

passed portion of the container for gripping it. A handle unit is connected to the coupling members for use in rotating the same and for use in carrying the gripped container.

5 In order that the principles of the invention may be readily understood, several embodiments thereof, but to which the application is not to be restricted, are shown in the accompanying drawings wherein:

10 FIG. 1 is a side elevational view of a milk bottle to which there has been attached a support device constructed in compliance with the invention;

FIG. 2 is an enlarged perspective view of the support device of FIG. 1;

15 FIG. 3 is an enlarged plan view of the support device of FIG. 2 taken substantially along the line 3—3 of FIG. 1 and showing the coupling members rotated to permit expansion of the sections which define the collar of the support device;

20 FIG. 4 is a view similar to the showing of FIG. 3 but illustrating the coupling members rotated to draw the collar sections tightly about the encompassed portion of the bottle;

FIG. 5 is an enlarged view taken along the line 5—5 of FIG. 3;

25 FIG. 6 is an enlarged view taken along the line 6—6 of FIG. 4;

FIG. 7 is a side-elevational view of a milk bottle to which there has been assembled a modified support device constructed in compliance with the invention;

30 FIG. 8 is an enlarged perspective view of the support device of FIG. 7, the support device being shown in its disassembled state;

FIG. 9 is a perspective view similar to the showing of FIG. 8 but illustrating the assembled support device in relaxed condition for attachment to a bottle;

35 FIG. 10 is an enlarged, cross-sectional view taken substantially along the line 10—10 of FIG. 9;

FIG. 11 is a plan view of the support device of FIG. 8, the coupling members being shown in rotated condition for drawing the collar sections tightly about the encompassed portion of the bottle;

40 FIG. 12 is a slightly enlarged view taken substantially along the line 12—12 of FIG. 10;

FIG. 13 is a view similar to the showing of FIG. 12 but illustrating rotation of the coupling member to draw the surrounded lugs closely together to develop the gripped condition shown in FIG. 11;

45 FIG. 14 is an enlarged side elevational view taken substantially along the line 14—14 of FIG. 13 and showing the detent means which act between the collar sections and the coupling member to hold the handle means in upright position relative to the collar sections;

50 FIG. 15 is a perspective view of another modified support device constructed in compliance with the invention;

FIG. 16 is an enlarged view taken substantially through the section 16—16 of FIG. 15;

55 FIG. 17 is an elevational view taken along the line 17—17 of FIG. 16;

60 FIG. 18 is a view similar to the showing of FIG. 17 but illustrating the handle unit rotated into carrying position;

65 FIG. 19 is an enlarged, fragmentary, side-elevational view showing the cooperation between a coupling member and collar lugs of yet another modified embodiment of the invention;

70 FIG. 20 is a side-elevational view of the embodiment of FIG. 19 but showing the handle element rotated into carrying position;

FIG. 21 is a reduced scale view of the support device

of FIGS. 19 and 20 assembled to a metal can for carrying the same;

FIG. 22 is a perspective view of still another modified embodiment of the invention in which the handle member is biased into generally lateral relationship with the collar elements, attachment of the support device to a milk bottle disposed in inverted position being shown to exemplify the normally laterally disposed location of the handle member;

FIG. 23 is a top plan view of the collar elements, 10 lugs and interconnecting ears of the support device of FIG. 22;

FIG. 24 is a side elevational view of the support device of FIG. 22 with the handle member shown in upright or carrying position relative to a milk bottle, 15 the handle member and collar elements being shown in section to reveal certain pertinent relationships;

FIG. 25 is a fragmentary plan view illustrating the reaction of the collar lugs and interconnecting ears during stretching of the collar elements to fit the support device to a container, the associated coupling element of the handle member being partially cut away and shown in section to reveal this reaction;

FIG. 26 is an enlarged perspective view of the coupling element showing the generally conical cam surface;

FIG. 27 is an enlarged plan view showing the coupling element in section and illustrating the cooperation of the collar lugs and coupling element in the upright or carrying position of the handle member; and

FIG. 28 is a view similar to the showing of FIG. 27 but illustrating the position of the parts in the normal position with the handle member disposed generally laterally of the collar elements.

Referring now in detail to the drawings, specifically to FIG. 1, a support device indicated generally by the numeral 20 is shown constructed in compliance with the invention and is illustrated as being attached to a glass, half-gallon milk bottle 22. In accord with conventional practices, the milk bottle 22 includes a neck portion 24, a radially outwardly flanged lip 26 and a radially outwardly extending ridge or bead 28. Conveniently, the support 20 is assembled to the milk bottle 22 at the neck portion 24 and beneath the bead 28.

Turning to FIG. 2, the support 20 is seen to include a number of arcuate bands or collar sections 30 which are arranged in an endless series and in substantially coplanar relationship. Each of the collar sections 30 is provided with a leading lug or cam follower 32 on one end and a trailing lug or cam follower 34 on the opposite end. The lugs 32 and 34 extend radially outwardly from the collar sections 30, and the leading lug 32 of one section is aligned with a trailing lug 34 of the next adjacent section. Each adjacent pair of leading and trailing lugs is interconnected by a centrally perforated ear 36, the aperture in each ear 36 opening into the space between the aligned lugs to permit a substantial enlargement of the effective diameter of the band which is defined by the several collar sections. The collar sections 30, the lugs 32 and 34 and the ears 36 are advantageously fabricated to be integral; and because of the separation between each adjacent pair of lugs and because of the perforated character of the attached ear, the collar sections 30 may be spread appreciably, as for example to negotiate the lip 26 and the bead 28 of bottle 22, without the need to rely on the resiliency of the material from which the collar sections are formed.

In compliance with an important feature of the invention, a rotatable coupling member 38 is associated with each adjacent pair of aligned leading and trailing lugs; and the coupling member 38 is fashioned with an opening or cam aperture 40 which surrounds the aligned pair of lugs. As will be recognized, this surrounding of the adjacent pair of lugs serves to interconnect the collar sections 30. A bail or handle member 42 is connected to each of the coupling members 38 both for use in rotat-

ing the same and for use in carrying the bottle 22 when the support device 20 has been assembled thereto. The handle member 42 advantageously includes a grip section 44 and two leg sections 46 which extend from the opposite ends of the grip section 44 in generally right angular relationship to merge with the coupling members 38.

With reference to FIG. 5, the opening 40 in the rotatable coupling member 38 is seen to take the outline of two overlapping circles whereby to define a substantially oval aperture with pointed formations 48 projecting toward each other across the minor diameter of the opening. Transversely of this minor diameter, the opening 40 defines a major diameter which allows a substantial spacing of the surrounded lugs 32 and 34 for ease in assembling the support 20 to the neck of the bottle 22. Cooperatively, the lugs 32 and 34 take semi-circular cross-section, as shown; and the diameter of the lugs is arranged to be slightly greater than the spacing between the formations 48 whereby to detent or lock both of the lugs selectively in either a different or the same circular region of the opening 40. The planar sides of the aligned lugs are disposed facing each other to hold the same against relative rotation or twisting when in the converged condition, and the surfaces of the lugs 32 and 34 and the surface of opening 40 contacted thereby comprise respective interference surfaces.

The various elements of the support 20 are advantageously fabricated from a tough resilient material, such as for example the polyolefinic plastics; and accordingly, the collar sections 30, the lugs 32 and 34 and the ears 36 may be readily molded in integral relationship. Similarly, the coupling members 38 and the handle member 42 may be molded integral. Thus, the support 20 is developed into a two-piece construction. When the collar sections are fabricated from a tough resilient material, they may be forcibly elongated to negotiate oversized containers. Moreover, while the ears 36 have been described as interconnecting the aligned pairs of leading and trailing lugs, it is desirable under some circumstances to provide the collar sections as completely separate elements whereby to develop a three-piece construction. In this latter case, the coupling members 38 serve to interconnect the collar sections at the respective lugs thereof. In either event, it is desirable to provide abutment means on the aligned lugs outwardly of the associated coupling members 38; and in the embodiment of FIGS. 1-6 the abutment means is provided by a shoulder 50 on each of the ears 36, shoulders 50 being well shown in FIGS. 3 and 4. These shoulders act to confine the coupling members in position with respect to the surrounded lugs. Because appreciable stretching of the collar sections 30 is not necessary in assembling the support device 20 to a container, the various components of the support device may be fabricated from a suitable metal if desired.

Reconsidering FIG. 5, the leg sections 46 of the handle unit 42 are seen connected to the coupling member 38 in general alignment with the major diameter of the opening 40 and transverse to the minor diameter thereof. The leg sections 46 are fashioned to be relatively stiff members, as by the provision of stiffening ribs 52, shown in FIGS. 2 and 3; and returning to FIG. 5, this stiffness of the leg sections 46 permits them to act as levers between the grip section 44 of the handle unit and the coupling members for use in rotating the coupling members. Upon rotation of the coupling members, the walls of the minor diameter of the opening 40 act to cam the surrounded lugs closely together from the spaced position shown in FIG. 5 to the converged position shown in FIG. 6; and this converging of the aligned lugs 32 and 34 draws the corresponding collar section 30 tightly about the encompassed portion of the bottle 22 for gripping the same, as is shown in FIG. 4. When the lugs 32 and 34 have been thus drawn together, the formations 48 act to preserve this converged condition of the lugs. Correspondingly,

the formations 48 prevent movement of the coupling member 38 relative to the lugs along the direction of the major diameter of the opening 40. The alignment of the leg sections 46 transversely of the minor diameter of the opening 40 acts to preserve the bottle-gripping condition of the collar sections 30 when the handle unit 42 is in carrying condition with the weight of the bottle suspended from the collar sections.

Having thus described the one construction of the invention, it is important now to state how the illustrated embodiment is used. Assuming that the support has been fabricated as a two-piece configuration, as shown, the handle unit 42 will be assembled to the interconnected collar sections 30 by forcing the ears 36 through the openings 40 until the coupling members 38 are disposed between the collar sections and the abutment means defined by the shoulders 50. The handle unit 42 will be disposed generally coplanar with the collar sections 30 as is indicated in solid outline in FIG. 1, and the respective pairs of lugs 32 and 34 will be spaced apart as is generally indicated in FIG. 5 in order to facilitate passage of the collar sections over both the lip 26 and the bead 28 and into the position indicated in FIG. 1. Thereafter and in order to situate the collar sections in gripping relationship relative to the neck of the bottle 22, the handle unit 42 will be lifted into the position shown in broken outline. Correspondingly, the handle unit acts to rotate the coupling members 38, camming the adjacent pairs of lugs 32 and 34 into converging relationship as is indicated in FIG. 6. This camming of the lugs serves to tension the collar sections 30, drawing them tightly about the encompassed portion of the bottle whereby to provide a firm grip thereof. If it is desired to remove the support 20 from the bottle 22, the foregoing procedure will be reversed; and when the aligned pairs of lugs are spaced apart, the collar sections and the entire support may be easily lifted off the bottle.

Thus, it will be apparent that the support of the invention is easily and quickly assembled to a bottle while in a relaxed condition, the support of the invention concomitantly providing a very tight grip of the bottle when such is desired. In addition, it will be apparent that the multiple-element support of the invention is arranged to preserve the connection of the several elements. The tight grip of the bottle which is established by the support is of relatively permanent, though selectively relaxable, nature.

While a particular embodiment of the invention has been thus far shown and described, it should be understood, of course, that the invention is not limited thereto since many modifications may be made. Therefore and turning to a consideration of FIGS. 8-14 a modified form of the support is shown to be indicated by the numeral 20a. Since the embodiment of FIGS. 8-14 is similar in some respects to the embodiment of FIGS. 1-6, like numerals have been used to designate like parts while the suffix letter "a" has been employed to distinguish those elements associated with the embodiment of FIGS. 8-14.

Although the embodiment of FIGS. 8-14 is characterized by numerous features, such as the fashioning of the collar sections 30a to take a relatively thin section and the provision of the lugs 32a and 34a to have a substantially square cross-section, the support 20a is distinguished principally by the connection of the lugs with conically shaped spuds 54 instead of ears, by the shaping of openings 40a elliptically and by the provision of cooperating detents acting between the collar sections 30a and the coupling members 38a to hold the handle unit 42a in upright position relative to the collar sections. Considering FIGS. 8, 9 and 10, the spuds 54 are seen interconnecting the aligned pairs of lugs 32a and 34a; and the coupling members 38a are fashioned with conical surfaces to cooperate with the conical surface of the co-

70
75

operating spuds 54 in defining a smooth, continuous surface at the juncture of the assembled parts.

With particular reference to FIG. 10, the inner margin of the coupling member 38a is seen fashioned with a larger aperture than the outer margin thereof, thus the opening 40a tapers from the inner to the outer margin of the coupling member. Accordingly, the spud 54 may be forced through the opening in the coupling member, the walls of the opening expanding resiliently and the spud collapsing resiliently to permit passage of the spud completely through the coupling member. Once the spud has emerged, the abutment defined by the shoulder 50a is disposed in contact with the outer edge of the coupling member to confine the coupling member in position with respect to the surrounded lugs. Advantageously, the outer aperture of the opening 40a is circular as is indicated at 56 in FIG. 8 whereas the inner aperture is oval as indicated at 58.

Turning to FIG. 14, the collar section 30a is seen fashioned with a triangular, outwardly extending rib 60 which confronts a triangular ridge 62 that protrudes from the coupling member 38a to face toward the corresponding collar section. A ridge 62 is provided at each edge of the coupling member 30a across the minor diameter thereof. Thus, the ridges 62 may coact with the triangular ribs 60 in holding the handle unit 42a in generally upright position relative to the collar sections. It is recognized that the lugs 32a and 34a may also be provided with triangular ribs similar to the triangular ribs 60 whereby to urge the handle unit 42a into generally coplanar relationship with the collar sections if and when such an arrangement is preferred to the upright condition which is preserved by the cooperation of ribs 60 and ridges 62. The surface of opening 40a and the surfaces of lugs 32a and 34a contacted thereby comprise cooperating interference surfaces; and in addition, the contacting surfaces of ribs 60 and ridges 62 comprise a second set of such surfaces.

Other than the described distinctions, the support 20a is constructed and functions similarly to the support 20.

Further modified embodiments of the invention are shown in FIGS. 15-18 and FIGS. 19-21 respectively. Since these later embodiments incorporate elements similar to those found in the previously described embodiments, like numerals have been used to designate like parts, the suffix letter "b" having been employed to distinguish those elements associated with the embodiment of FIGS. 15-18 and the suffix letter "c" having been employed to distinguish those elements associated with the embodiment of FIGS. 19-21.

The support 20b which is illustrated in FIGS. 15-18 is particularly characterized by the structure and manner of connecting the leading lugs 32b with the respective trailing lugs 34b. Specifically, a formation 64 of generally circular outline is employed for this purpose. As is best shown in FIGS. 16 and 17, the formation 64 interconnects the outer ends of the lugs 32b and 34b. In addition, the formation 64 includes relatively thick sections 66, marginal abutment elements 68 disposed radially outwardly of the relatively thick sections 66, and a relatively thin medial section 70. Advantageously, the medial section 70 takes substantially oval shape whereby to permit the abutment element 68 to merge forming an annular shoulder 72 which serves to confine the associated coupling member 38b in position with respect to the surrounding lugs 32b and 34b.

The relatively thin medial section 70 is aligned with the space between the lugs 32b and 34b and functions as a hinge for the relatively thick sections 66. Thus, the formation 64 may be folded about the relatively thin section 70 to converge the relatively thick sections 66 for facilitating passage of the formation 64, particularly the marginal abutment elements 68 through the cam aperture 40b and the coupling member 38b. Such an

arrangement simplifies the assembly of handle unit 42b and the collar sections 30b.

It is also to be observed that the medial section 70 includes an inner portion 74 that is disposed closer to the center of the aligned collar sections 30b than the plane defined by the annular shoulder 72. This arrangement of the formation 64 tends to exclude dirt and foreign matter from the region between the aligned lugs 32b and 34b, thus enhancing the sanitary qualities of the support 20b. This latter function is achieved if the inner surface of the portion 74 is at least coplanar with the shoulder 72 and preferably situated inwardly thereof.

The support 20c which is shown in FIGS. 19-21 is characterized principally by the shape of the opening or cam aperture 40c in the coupling members 38c. As is well shown in FIGS. 19 and 20, the opening or cam aperture 40c is fashioned to take an ovoid shape with the large end thereof toward the grip section 44c of the handle member 42c. In use, the lugs 32c and 34c which are received in the cam aperture 40c tend to reside in the large end of the cam aperture as is shown in FIG. 19. When the grip section 44c of the handle unit 42c is grasped to lift the container to which the support 20c is assembled, the weight of the container acts generally perpendicular to the plane of the aligned collar sections 30c, that is, in the direction indicated in FIG. 20 by the numeral 76. Since the act of picking up the container by grasping and lifting the handle unit 42c serves to rotate the coupling member 38c into the position shown in FIG. 20, the weight of the container tends to draw the surrounded lugs 32c and 34c into the lower, narrower end of the cam aperture 40c. This action converges the surrounded lugs and draws the collar sections 30c into gripping engagement with the encompassed portion of the container. However, when the container is placed down and the handle unit is released, the tension stored in the collar sections 30c and in the lateral portions of the coupling member 38c tends to bias the handle unit 42c into generally coplanar relationship with the collar sections, thus rotating the handle unit out of its upright position and in the general direction indicated in FIG. 20 by the numeral 78. The wall of aperture 40c and the contacted surfaces of lugs 32c and 34c comprise a set of cooperating interference surfaces.

The support 20c is shown in FIG. 21 to be assembled to a relatively large metal can 80 beneath the upper bead or top double seam 82 thereof. When the collar sections are made of a flexible material, the support of the invention may accommodate and be assembled to cans of either round or non-round section. Similarly, the support of the invention is capable of being assembled to and packaging together a group of cans or other containers.

A yet further modified embodiment of the invention is shown in FIGS. 22-28 wherein like numerals have been used to identify elements which are similar to those found in the previously described embodiments. The suffix letter "d" has been used to distinguish those like elements associated with the embodiment of FIGS. 22-28.

The support device 20d is particularly characterized by its being arranged so that the handle member 42d is normally biased into a generally lateral relationship with the collar sections 30d, a position indicated in FIG. 22. It is desirable to have the handle member normally disposed in this position so that, when the support device is assembled with a glass bottle, such as a milk bottle, and when such assemblage is to be cleaned and sterilized in conventional bottle-washing equipment, the handle member does not obstruct the open mouth of the bottle. In other words, the support device 20d is arranged so that force must be applied thereto in order to raise the handle to the upright or carrying position shown in FIG. 24, some of this force being stored in the support device itself to provide a returning action of the handle mem-

ber to its generally laterally aligned condition upon being released from its upright position.

The support device 20d is characterized by a number of structural features that are arranged to promote the desired effect described hereinabove. Among these is the arrangement of the lugs or cam followers 32d and 34d to include angled leg portions 83 shown in FIG. 23. These angled leg portions are arranged, in each adjacent pair of the lugs, to cooperate in defining a pyramidal cam formation having its base at the arcuate bands or collar sections 30d. The apex of this pyramidal cam formation disappears into straight outer portions 84 of the respective lugs 32d and 34d.

It should be noted, with reference to FIG. 25, that, although the leg portions 83 are angulated, they have substantially parallel opposite sides. Accordingly, the leg portions 83 define an opening 85 of substantially triangular outline therebetween. So arranged, hinges or pivot points 86, 88 and 90 are developed respectively at the juncture of the leg portions 83 and collar sections 30d, at the juncture of leg portions 83 and the straight portions 84, and at the mid-portion of the interconnecting ear 34d. Flexure occurs at these pivot points whereby to facilitate expansion of the opening defined by the collar sections 30d in assembling the support device to a container. It should also be observed, with reference to FIG. 25, that the collar sections 30d are fashioned with extension portions 92 that extend toward each other across the base of the pyramidal cam formation. These extension portions enhance the gripping of the container particularly at the lip or bead beneath which the collar sections are normally disposed.

Considering FIG. 26, the same aperture 40d is seen to be fashioned with a major diameter 94 that is aligned generally with the longitudinal axis of the leg section 46d. Cam aperture 40d also includes a minor diameter 96. The leg sections 46d and the grip section 44d of the handle member are, in addition, arranged to reside substantially in a single plane; and thus, the major diameter of the cam aperture 40d is generally aligned with the plane of the handle member 42d. This major diameter of the cam aperture is also arranged to have a size of at least about the major basal dimension of the pyramidal cam formation defined by the adjacent lugs 32d and 34d. This dimensional relationship is illustrated in FIG. 25. The minor diameter of the cam aperture 40d, on the other hand, is arranged to have a size of less than the major basal dimension of the cam formation. This dimensional relationship is shown in FIG. 27 where the coupling member 38d is seen to have ridden outwardly on the leg portions 83 in view of the minor diameter 96 having been rotated into alignment across the pyramidal cam formation.

The functioning of the support device 20d will now be described with continued reference to FIGS. 27 and 28. Because the major diameter 94 of the cam aperture 40d takes a size of at least about the major basal dimension of the cam formation, the cam formation, comprising the leg portions 83, and the coupling member 38d assume a stable, substantially unstressed or relaxed condition when the handle member 42d is generally aligned with the collar sections 30d laterally thereof as shown in FIG. 28. It is to be recognized that some slight mechanical interference between the cam formation and the cam aperture may exist in this condition in order that the collar sections 30d will tightly grip the encircled container. This generally relaxed or normal condition of the handle member relative to the collar sections is also illustrated in FIG. 22.

Because the minor diameter 96 is selected to have a size of less than the major basal diameter of the cam formation, the coupling member 38d and the leg portions 83 encompassed thereby assume an unstable, stressed condition when the handle member is disposed across the collar sections 30d in the upright or carrying position

which is illustrated in FIG. 24. In this latter position, the major diameter 94 is upright, as is shown in FIG. 24, and the transverse minor diameter 96 is situated generally in the plane of the leg portions 83 and the collar sections 30d, as is shown in FIG. 27. In order to assume this latter position, the coupling member 38d must ride outwardly because of the angulation of the cam formation comprised of the leg portions 83. The relative size of the minor diameter 96 also tends to draw the ends of the respective collar sections 30d closer together stretching these sections and storing force therein. Some deformation of the leg portions 83 and the coupling member 38d is also frequently experienced. Since the material which the various elements are fabricated is resilient, this deformation stores additional force in the support device, which force tends to return the handle from the upright position to the position aligned generally laterally of the collar sections when a transient force is applied to the handle means displacing it slightly from the carrying position. As will be recognized, the relative dimensions can be selected so that no initiating force is necessary to return the handle member from the upright to the lateral position. In essence, the cam formation defined by the angled leg portions 83 and the cam aperture 40d in the coupling member 38d are cooperatively shaped to define a cam peak corresponding to the upright carrying position of the handle member 42d and a cam trough corresponding to the generally laterally aligned position of the handle member whereby to return the handle member to its lateral position upon release of the handle member from its upright position.

In order to enhance the defined action of the support device 20d, the coupling member 38d is provided with a generally conical cam surface 98 shown in FIG. 26. The cam surface 98 corresponds in its direction of taper with the cam formation defined by the leg portions 83, as will be apparent from an inspection of FIGS. 27 and 28. Accordingly, the cam formation defined by the leg portions 83 engages the cam aperture 40d in a fitted manner. Relative rotation of the handle member 42d is facilitated by this arrangement. In addition, the endless collar sections 30d are advantageously disposed to form an oval in the as-molded condition which is shown in FIG. 23, the major axis 100 of this oval being aligned with the oppositely disposed pairs of lugs 32d and 34d. Assembly of a support device with collar sections so arranged to a round portion of a container develops stress in the collar sections, and this stress tends to spread each cooperating pair of lugs to develop further resistance to the positioning of the handle member in the carrying position. As will be recognized, the conical surface of aperture 40d and the surfaces of leg portions 83 that are contacted thereby comprise cooperating interference surfaces.

In accordance with another feature of the invention, the grip section 44d of the handle member 42d is selected to possess a greater span than the collar sections 30d. Furthermore, the leg sections 46d of the handle member are angled to dispose the coupling members 38d in the unstressed condition associated with the lateral position of the handle member. Subsequent displacement of the coupling members to the stressed condition of the parts develops supplemental stress in the connected grip and leg sections of the handle member, and this latter stress enhances the biasing of the handle member toward its lateral position.

With reference to Figs. 24 and 26, the handle member 42d is seen to comprise a strap portion 102 and a ridge portion 104, these portions being arranged to develop a T-shaped cross-section in the handle member. Such a section provides a comfortable grip at the rounded inward surface of the strap portion while additionally providing stiffness and resistance to bending through the reinforcement provided by the ridge portion 104.

The specific examples herein shown and described are

to be considered as being primarily illustrative. Various changes beyond those described will, no doubt, occur to those skilled in the art; and such changes are to be understood as forming part of this invention insofar as they fall within the spirit and scope of the appended claims.

The invention is claimed as follows:

1. A carrier for containers and the like, said carrier comprising: a plurality of bands arranged in an endless series; a first cam follower on one of said bands; a second cam follower on an adjacent band; a coupling member having a cooperating complementary cam aperture receiving said first and second cam followers in rotatably slidible relationship therewith, said cam aperture having a first dimension which accommodates spacing apart of the cam followers whereby to enlarge the effective length of the endless series of bands for assembly of the carrier to a container, said cam aperture further having a second, smaller dimension which demands a closer spacing of said followers whereby to reduce the effective length of the endless series of bands for causing said bands to grip the container; handle means connected to said coupling member for use in carrying a container assembled with said carrier and for use in rotating said coupling member relative to said followers whereby to direct the spacing thereof; and a formation interconnecting the ends of said followers away from said bands, including relatively thick sections, abutment elements outwardly of said relatively thick sections acting to confine said coupling member in position with respect to said followers, and a relatively thin medial section aligned with the space between said followers whereby to define a hinge for said relatively thick sections, converging of said relatively thick sections about said hinge facilitating passage of said abutment elements through said cam aperture for assembling said handle means to said bands.
2. A carrier according to claim 1 wherein one of said coupling members and said formation is of tough, resilient material.
3. A support according to claim 1 wherein said cam aperture is elliptical.
4. A support according to claim 1 wherein said cam aperture is ovoid.
5. A support according to claim 1 wherein said handle means includes a grip member and wherein said cam aperture is ovoid with the large end thereof toward said grip member whereby said handle means is biased normally into coplanar relationship with said bands.
6. A support according to claim 1 wherein said cam aperture takes the outline of two overlapping circles.
7. A support for containers and the like, said support comprising: a plurality of collar sections arranged in an endless series and in substantially coplanar relationship; outwardly extending lugs connected to each of said collar sections adjacent the opposite ends thereof, a leading lug of one section being aligned with a trailing lug of the next adjacent section; a rotatable coupling member for each adjacent pair of said aligned leading and trailing lugs, said coupling member having an opening surrounding said aligned lugs whereby to interconnect said collar sections, said opening having a major diameter which allows situation of the surrounded lugs in spaced-apart condition for assembly of the support to a container and said opening further having a minor diameter which, upon rotation of said coupling member, acts to cam said surrounded lugs into closely disposed condition for drawing said collar sections tightly about the encompassed portion of the container for gripping the same; handle means connected to said coupling members for use in rotating the same; and detent means including a first interference surface on said coupling member and a cooperating, second interference surface on the assembly comprising said collar sections and said lugs, said first and second interference surfaces being relatively arcuately situated for positioning in maximum interfering engagement when

said lugs are disposed in one of said conditions and for positioning in minimum interfering engagement when said lugs are disposed in the other of said conditions whereby said detent means act to bias said handle means into a selected position relative to said collar sections.

8. A support for containers and the like, said support comprising: a plurality of collar sections arranged in an endless series; outwardly extending lugs connected to each of said collar sections adjacent the opposite ends thereof, a leading lug of one section being aligned with a trailing lug of a next adjacent section; a rotatable coupling member for each adjacent pair of said aligned leading and trailing lugs, said coupling member having an opening surrounding said aligned lugs whereby to interconnect said collar section, said opening having a major diameter which allows spacing of the surrounded lugs for assembly of the support to a container and said opening further having a minor diameter which, upon rotation of said coupling member, acts to cam said surrounded lugs closely together for drawing said collar sections tightly about the encompassed portion of the container for gripping the same; and handle means connected to said coupling members for use in rotating the same, each adjacent pair of said leading and trailing lugs including angled leg portions cooperating to define a pyramidal cam formation having its base at said collar sections, said handle means being substantially planar, and the major diameter of the opening in the cooperating coupling member being generally aligned with the plane of said handle means and having a size of at least about the major basal dimension of said cam formation whereby said lugs and cooperating coupling members assume a stable, substantially unstressed condition when said handle means is generally aligned with said collar sections laterally thereof, said minor diameter having a size of less than said major basal dimension whereby said lugs and cooperating coupling members assume an unstable, stressed condition when said handle means is disposed across said collar sections in upright carrying position, transient force applied to said handle means in said carrying position initiating displacement of said handle means to its lateral position.

9. A support for containers and the like in accordance with claim 8 wherein said coupling member has a generally conical cam surface corresponding in its direction of taper with said cam formation whereby to facilitate relative rotation of said handle means.

10. A support for containers and the like in accordance with claim 8 wherein said collar sections have extension portions extending toward each other across the base of said pyramidal cam formation whereby to enhance the gripping of the assembled container.

11. A support for containers and the like in accordance with claim 8 wherein said handle means is of resilient material and includes a grip section and leg sections connecting said grip section to said coupling members, said grip section having a greater span than said endlessly arranged collar sections and said leg sections being angled to dispose said coupling elements normally in said unstressed condition, displacement of said coupling members to said stressed condition developing stress in said connected grip and leg sections whereby to enhance the bias of said handle means toward its lateral position.

12. A support for containers and the like in accordance with claim 8 wherein said endlessly arranged collar sections are disposed forming an oval, the major axis of said oval being aligned with two adjacent pairs of lugs whereby assembly of said collar sections to a round portion of a container develops stress in said sections tending to spread each pair of said two pairs of lugs whereby to develop further resistance to the positioning of said handle means in said carrying position.

13. A carrier for containers and the like, said carrier comprising a plurality of bands arranged in an endless series; a first cam follower on one of said bands; a second cam follower on an adjacent band, said followers including leg portions cooperating to define a pyramidal cam formation having its base at said bands; a coupling member having a cooperating complementary cam aperture receiving said first and second cam followers in rotatably slidable relationship, said cam aperture having a first dimension which accommodates spacing apart of the cam followers whereby to enlarge the effective length of the endless series of bands for assembly of the carrier to a container, said cam aperture further having a second, smaller dimension which demands a closer spacing of said followers whereby to reduce the effective length of the endless series of bands for causing said bands to grip the container; and handle means connected to said coupling member for use in carrying a container assembled with said carrier and for use in rotating said coupling member relative to said followers, said handle means being substantially planar and said first dimension of the cam aperture being generally aligned with the plane of said handle means and having a size of at least about the major basal dimension of said cam formation whereby said cam formation and said coupling member assume a relaxed condition when said handle means is generally aligned with said bands laterally thereof, said second, smaller dimension having a size of less than said major basal dimension, said cam formation and said cam aperture being cooperatively shaped to define a cam peak corresponding to the upright carrying position of said handle means and a cam trough corresponding to the generally laterally position of said handle means whereby to return said handle means to said last named position upon release of said handle means from said upright position.

14. A support according to claim 7 wherein one of said interference surfaces is substantially cusp-shaped in outline.

15. A support according to claim 7 wherein said first interference surface is generally ovoid.

16. A support according to claim 7 wherein said first and second interference surfaces are conical.
